US00D529781S

(12) **United States Design Patent** (10) **Patent No.:** **US D529,781 S**
Yale (45) **Date of Patent:** **** Oct. 10, 2006**

(54) **FOLDED MULTIPURPOSE HAND TOOL
WITH ANGULAR END PROFILE**

5,142,721 A 9/1992 Sessions et al.

(Continued)

(75) Inventor: **Melissa C. Yale**, Portland, OR (US)

FOREIGN PATENT DOCUMENTS

(73) Assignee: **Leatherman Tool Group, Inc.**,
Portland, OR (US)EP 0676261 A1 10/1995
EP 0783937 A2 11/1996
GB 5375 of 1882
IT 521555 3/1955(**) Term: **14 Years**(21) Appl. No.: **29/220,831**

McClung & Stenzel, LLP(57) **CLAIM**The ornamental design for a folded multipurpose hand tool
with angular end profile, as shown and described.**DESCRIPTION**FIG. 1. is an isometric view from the upper right front of a
folded multipurpose hand tool with angular end profile,
including my new design;

FIG. 2. is a top plan view thereof;

FIG. 3 is a right side elevational view thereof;

FIG. 4 is a left side elevational view thereof;

FIG. 5 is a bottom plan view thereof;

FIG. 6 is a front end elevational view thereof; and,

FIG. 7 is a rear end elevational view thereof.
